UNITED STATES PATENT OFFICE.

JOHN G. FRIBERG, OF MAIDEN ROCK, WISCONSIN, ASSIGNOR OF ONE-THIRD TO GEORGE E. BRASINGTON, OF MAIDEN ROCK, WISCONSIN, AND ONE-THIRD TO OSCAR H. ANDERSON, OF PLUM CITY, WISCONSIN.

HORSE-COLLAR.

1,129,659.

Specification of Letters Patent. Patented Feb. 23, 1915.

Application filed September 2, 1914. Serial No. 859,838.

To all whom it may concern:

Be it known that I, JOHN G. FRIBERG, a citizen of the United States, residing at Maiden Rock, in the county of Pierce and State of Wisconsin, have invented new and useful Improvements in Horse-Collars, of which the following is a specification.

This invention relates to horse collars and it consists in the novel features hereinafter described and claimed.

An object of the invention is to provide a horse collar of simple and durable structural arrangement which is adapted to be easily and quickly adjusted to fit the necks of animals of different sizes.

With the above object in view the invention consists in making the upper side portions of the collar relatively thin and pliable and in providing the said thin and pliable portion with openings adapted to register with each other. In conjunction with the collar made as above indicated a combined neck piece and buckle is used the said neck piece and buckle consisting of a metallic strip of anticlastic configuration having a similar plate of leather secured to the end portions thereof. The said plate of leather is adapted to bear against the upper portion of the neck of the animal. A keeper, consisting preferably of a leather strap is secured at its ends to the metallic strip at one edge thereof and is adapted to receive the end portions of a collar. The said metallic strip is further provided with upstanding studs adapted to pass through the registering openings of the end portions of the collar and these studs are provided with perforations through which a flexible member as for instance a leather string may be passed for the purpose of holding the end portions of the collar down in proper position upon the studs.

In the accompanying drawing:—Figure 1 is a perspective view of a portion of the collar. Fig. 2 is a side elevation of the upper portion of the same. Fig. 3 is a sectional view of the same taken on the line 3—3 of Fig. 2. Fig. 4 is a detailed perspective view of the buckle and neck piece of the collar.

The collar 1 is provided with relatively thin and pliable portions 2 at the upper

ends of the sides of the said collar. These portions are provided with openings 3 adapted to register with each other when the end portions of the collar are overlapped with relation to each other. Used in conjunction with the collar made as hereinbefore stated is a combined buckle and neck piece the same consisting of a metallic strip 4 which is of anticlastic configuration. A leather plate 5 of similar configuration is secured at its edges to the ends of the strip 4. A keeper 6 is attached at one edge of the strip 4 and the said keeper preferably consists of a strap of leather. Studs 7 are mounted upon the strip 4 and are provided with perforations 8. When the end portions of the collar are overlapped and the openings thereof are brought into register with each other the studs 7 are passed up through the registering openings and the overlapping end portions of the collar are passed through the keeper 6. A leather string 9 is secured to the plate 5 and may be passed through the perforations 8 above the overlapping end portions of the collar and thus the said string serves as means for holding the overlapping end portions of the collar down in proper position upon the upstanding studs 7.

From the above description taken in conjunction with the accompanying drawing it will be observed that a flexible and an adjustable collar is provided and that the parts may be easily and quickly manipulated to place the collar in position upon the neck of an animal and to remove the same therefrom.

It is to be understood that minor changes in details of construction may be resorted to without departing from the spirit of the invention as expressed in the claims.

Having described the invention what is claimed is:—

In combination with a collar having comparatively thin and pliable end portions adapted to overlap each other and provided with registering openings, a combined buckle and neck piece including a metallic strip of anticlastic configuration, a plate of leather of similar configuration secured to the forward and rear ends of the strip,

spaced studs standing up from the strip and provided with openings, a string attached to the plate and adapted to pass through the openings, and a keeper secured at its ends 5 to the strip at points fixed with relation to the studs and adapted to receive the end portions of the collar.

In testimony whereof I affix my signature in presence of two witnesses.

JOHN G. FRIBERG.
